UNITED STATES PATENT OFFICE.

ROY D. CONWAY, OF EAST ORANGE, NEW JERSEY, ASSIGNOR TO WESTERN ELECTRIC COMPANY, INCORPORATED, OF NEW YORK, N. Y., A CORPORATION OF NEW YORK.

ALARM SYSTEM FOR AUTOMATIC TELEPHONE EXCHANGES.

Application filed December 29, 1922. Serial No. 609,571.

To all whom it may concern:

Be it known that I, Roy D. Conway, a citizen of the United States of America, residing at East Orange, in the county of 5 Essex and State of New Jersey, have invented certain new and useful Improvements in Alarm Systems for Automatic Telephone Exchanges, of which the following is a full, clear, concise, and exact 10 description.

This invention relates to coin collection for automatic telephone exchanges and is an improvement upon my invention disclosed in Patent No. 1,491,337 of April 22, 15 1924, entitled "Coin collect system for automatic telephone exchanges."

Its object is to give an alarm at the central office, if the subscribers attempt to secure connections without depositing the required 20 coins.

In the system of said application, the deposit of a coin grounds one side of the line through the coin box magnet and an impulse of current is automatically applied 25 to the calling line to operate said magnet to cause it to collect or refund the coin and remove said ground when the calling party replaces his receiver. In said application, means is disclosed for operating an alarm 30 signal at the exchange if the ground is not removed when the coin box magnet operates and the operating impulse ceases, but no alarm is given if a ground is applied when the call is initiated and removed before the 35 calling party replaces his receiver to break down the connection. Thus, a subscriber could apply a ground in making a call and thus obtain control of the impulse circuit for setting the central office automatic switches, 40 build up his connection, and after talking, but before replacing his receiver, could remove the ground and no alarm would be given on the replacement of the receiver and the restoration of the automatic central 45 office switches.

It is the object of this invention to render it still more difficult to "beat" the coin boxes without detection, and this invention consists in a circuit arrangement whereby a 50 test is made of the calling line when the coin collect circuit functions and if at that time the calling line circuit is not in the condition it would be if a coin had been dropped in the coin chute an alarm signal

is given at an attendant's board at the exchange, as well as if the calling line circuit is not restored to its normal condition, as it should be, by the operation of the coin box magnet and the cessation of its operating impulse. 55

Referring to the drawings, Fig. 1 shows a calling line, a primary line switch and the coin control circuit; Fig. 2 shows a secondary line switch, a selector, a connector and the called line. 60

The invention will be more readily understood from a detailed description of the operations involved in setting up a connection. 65

Upon the removal of the receiver at the calling substation, the relay 101 of the primary line switch PLS individual to the calling line is operated over the calling line circuit. In attracting its armature it closes a circuit including the pull down winding 102 of the line switch which causes the line switch to seize the preselected trunk by operating the set of springs in the well known manner, as shown and particularly described, for example, in Patent No. 1,304,- 70 369, to A. J. Ray of May 20, 1919. The calling line is now extended to the trunk circuit, whereupon relay L is operated as follows: free pole of battery, contact 104 of relay Y, conductor 105, contact 106 of relay S', conductor 107, contact 103 of relay N N, resistance 187, conductors 109, 110, 128, the inner right armature and back contact of relay B, lower armature and back contact of relay A, ring conductor 165, contacts 162 and 163 of the line switch, conductor 153, the telephonic loop at the calling substation, tip conductor 164, springs 166 and 167 of the line switch, conductor 158, upper armature and back contact of relay A, left armature and back contact of relay B, retardation coil 188, relay L, outer left armature and back contact of relay N N to ground. 75

Relay L closes a circuit for the cut-off winding 100 of the line switch to hold the line switch set before the circuit for the pull down winding 102 is opened as the line relay 101 releases. The circuit for the cut-off winding is as follows: ground, left armature and front contact of relay L, conductor 108, outer right armature and back contact of relay H H, conductor 199, contact 198 of relay N N, conductor 146, release or sleeve 80

80

85

90

95

100

105

conductor 125, springs 112, 113, cut-off winding 100, secondary 197 of induction coil 10 to free pole of battery.

- When the primary line switch PLS operated and closed springs 114 and 115, the following circuit was closed to operate the secondary line switch SLS to seize an idle first selector; grounded spring 115, spring 114, secondary line switch holding conductor 116, outer left armature and back contact of relay H H, conductor 117, conductors 201 and 202, pull-down coil 203 of the secondary line switch, contact 204, conductor 205, slow relay 206, to free pole of battery.
- 15 The secondary line switch SLS in operating closes a locking circuit for itself, including its windings 207 and 203 in series, contact 208, to grounded holding conductor 201.
- 20 Relay L, in attracting its left armature, operates slow-to-release relay N, which operates relay N N. Relay N N in attracting its outer left armature removes a short circuit from about the high resistance 118 for 25 a purpose which will shortly appear, and in attracting its inner left armature grounds the release conductor 125 over conductor 146 to hold up the primary line switch PLS after relay L releases. Relay N N in attracting its inner right armature at 103 substitutes relay RT for resistance 187 in the calling line circuit. Relay RT is thus connected to the ring side 153 of the calling line. Relay RT is marginal and will 30 not operate over the line circuit in series with relay L and resistance 118. Resistance 118 is normally short circuited, its short circuit being removed when relay N N operates to increase the margin of operation of relay RT.

The circuit remains in this condition until the calling party inserts a coin in the coin box. The coin box may be of the type shown and described in Patent No. 1,043,219, to O. F. Forsberg, issued November 5, 1912. As shown and described in detail in said patent, the deposited coin causes the closure of contact 13 thus grounding the tip side of the line 164, and since the receiver is now removed from its hook, this ground is also connected to the ring side of the line 153. The application of this ground closes a shunt about relay L and the high resistance 118, whereupon the marginal relay RT 45 operates over a circuit including the ring side of the line 153, the calling substation receiver hook, magnet M to ground closed by contact 13 of the coin box.

Relay RT in operating, energizes relay S' over the following circuit: battery, armature and front contact of relay RT, conductor 121, relay S', conductors 122, 123, outer left armature and front contact of relay N N to ground. In attracting its 50 outermost left armature, relay S' connects

conductor 116 to conductor 117 independently of the outer left armature and back contact of relay H H. In attracting its middle left armature, relay S', provides a direct path to ground through coil 188 from 70 the tip side 164 of the line short circuiting relay L and resistance 118. Relay L releasing, opens the circuit of relay N which is slow to release. In attracting its innermost left armature, relay S' connects the 75 impulse relay R' to the ring side 153 of the line. In attracting its innermost right armature it removes relay RT from the calling line circuit and locks itself to battery at a normal contact of relay Y and 80 to the grounded sleeve or release conductor 124. This conductor was grounded when the secondary line switch seized the first selector in the well known manner. The locking circuit of relay S' is as follows: free pole of battery, contact 104 of relay Y, conductor 105, inner right armature and front contact of relay S', relay S', conductor 122, to grounded sleeve wire 124. In attracting its outermost right armature, it 85 operates relay H H and slow relay H. The circuit for relay H H leads over conductor 176 and the outer right armature of relay B and conductor 189. Relay H then locks itself over conductors 174, 176, outer right 90 armature and back contact of relay B, conductor 189, to battery at its own armature and front contact. Relay H H being connected to conductor 189 is also held up by the armature of relay H.

Relay H H in attracting its inner right armature, connects grounded conductor 148 over conductor 147 to the release conductor 125, leading back to the primary line switch to maintain the cut-off winding 100 thereof 10 energized independently of the ground supplied at the inner left armature of relay N N, which relay releases when slow relay N releases, the circuit of relay N having been opened as relay L was short circuited when relay S' operated. The grounded conductor 148 is however extended to the sleeve conductor 125 by relay H H before relay N, which is slow to release, falls back.

The calling party now operates his sender in accordance with the first digit of the wanted number, and on the return of the sender to its normal position, the following circuit including the impulse relay R' is interrupted: battery, relay R', conductor 126, innermost left armature and front contact of relay S', conductors 127, 128, inner right armature and back contact of relay B, lower contacts of relay A, the ring side 153 of the line, the substation loop, the tip side 164 of the line, the upper back contacts of relay A, left armature and back contact of relay B, retardation coil 188 to ground at the middle left armature of relay S'. The ground connected to the tip side of the line at 13

does not interfere with this impulse circuit. Upon the initial operation of the impulse relay R' before the sender was operated, it closed at its lower front contact a circuit 5 for slow-to-pull-up relay D which in operating extended the front contact of relay R' to energize relay D D which connected the incoming and outgoing ends of the tip and ring conductors together, these conductors 10 including a pair of condensers 129, 130. Upon the first retraction of the armature of impulse relay R', due to the sender interrupting the line, relays D and D D instantly retract their armatures, the latter 15 disconnecting the incoming tip and ring conductors from the outgoing tip and ring conductors. Relay D is constructed and arranged so that it will not again attract its armatures while the impulse relay armature 20 is vibrating. Relay D D thus remains inert during this period to maintain the condensers disconnected from the outgoing ends of the tip and ring conductors to prevent interference with the character of the impulses, by the discharge of the condensers.

Only parts of the switches S and C are shown, since these switches are well known. They may be of the type shown in Reissue Patent No. 13,901, issued April 13, 1915 to

30 F. Newforth, Jr.

Assuming that the selector S and preceding switches have been set and the calling line extended to the connector C, the impulse relay 210 (Fig. 2) of the connector C 35 is operated over the following circuit: free pole of battery, right winding of relay 210, normal contact of relay 211, conductor 233, ring conductor 212, multiple terminal 213 and brush 214 of the selector S, ring conductor 215, secondary line switch contact 216, ring conductors 232, 132, (Fig. 1) contact 133 of relay J, conductor 134, upper armature and front contact of relay R', conductors 135 and 136, armature 137, conductor 138, polarized relay P, tip conductor 139, contact 140 of relay J, tip conductors 195 and 225, contact 226, tip conductor 227, brush 228, terminal 229 of selector S, tip conductor 230, conductor 231, normal contact of relay 211, left winding of relay 210 to ground. Relay 210 at its front contact 40 operates slow relay 240, which interposes a break in the circuit of release magnet 241 and grounds the sleeve wire 245 to hold the 45 operated switches set in the well known manner.

The operations of setting the connector need not be described since they are well known and form no part of this invention. 50 The impulse relay R', which is in circuit with the sender, at its upper armature and front contact controls the circuit of the connector impulse relay 210.

When the connection has been built up to 55 the called line, the response of the called

party operates relay 211 which reverses the flow of current in the tip and ring conductors leading back to the coin collect circuit. Relay P, which is polarized, thereupon operates, closing a circuit for relay C 70 to prepare a circuit including the coin collect source C C and the calling line which circuit will be closed during the breaking down of the connection. The circuit for relay C is as follows: free pole of battery, 75 relay C and its normal upper contact, conductor 142, armature and alternate contact of relay P, conductors 192 and 157, to the grounded release wire 125. Relay C in attracting its armature 155 locks itself to 80 grounded sleeve wire 125. Relay J is also energized over the following circuit due to the operation of relay P: free pole of battery, resistance 184, relay J, conductor 150, armature and normal contact of relay K, 85 conductor 142, alternate contact and armature of relay P, conductors 192 and 157, to grounded sleeve wire 125. Relay J locks itself over its armature 152, conductors 151 and 157, to grounded sleeve wire 125. Relay J reverses the connections of the tip and ring conductors 195 and 132 with the tip and ring conductors 139 and 134, for a purpose which will appear later. Relay C in 90 operating, closes the following circuit for relay A: free pole of battery, relay A, conductor 154, uppermost armature and front contact of relay C, to the grounded sleeve conductor 124. Relay A extends the tip and ring conductors 158 and 165 leading from the primary line switch to the tip and ring conductors 168 and 161 of the trunk, cutting off the bridge containing the impulse relay R' and retardation coil 188. Relay R' in releasing its upper armature removes 95 the bridge containing the impedance coil 181 from across the talking conductors.

The subscribers may now converse. Talking current is fed from the connector to the calling line over the following circuit: free pole of battery, right winding of relay 210, outer armature and front contact of relay 211, (now operated) conductors 231, 230, terminal 229, brush 228, conductor 227, contact 226, conductors 225, 195, contact 159 of 110 relay J, conductors 134, 160 and 161, lower armature and front contact of relay A, contact springs 162 and 163, conductor 153, through the substation talking-set, conductor 164, springs 166 and 167, upper armature and front contact of relay A, conductor 168, relay P, conductors 139 and 170, armature 169 and front contact of relay J, conductor 132, conductor 232, contact 216, conductor 215, brush 214, terminal 213, conductors 212 and 233, inner armature and front contact of relay 211, left winding of relay 210 to ground. Current is fed to the called line over the windings of relay 211.

When the calling party replaces his re-

180

ceiver, relay 210 releases and ground is removed from the sleeve conductors 245, 237, 235 and 124, by the consequent release of slow relay 240, which causes the connector and selectors to restore. The removal of this ground also releases relay S', which in releasing its outermost left armature releases the secondary line switch SLS. Relay S' at its outer right armature and back contact also closes a circuit for relay Y as follows: free pole of battery, outer right armature and back contact of relay S', conductor 171, relay Y, contact 172 of said relay, conductor 173, inner left armature and alternate contact of relay H H, lower contact of the constantly operating interrupting machine I to ground. Relay H is still locked up, holding itself and relay H H operated and consequently the primary line switch remains set. Relay Y in operating, locks itself to grounded conductor 148 by closing its contact 177.

When the interrupting machine I next closes its upper contact, a circuit is closed to operate relay B by way of the inner left armature and front contact of relay Y. Relay B in attracting its armatures impresses positive current of preferably 110 volts from the collect source C C to the calling line to operate the polarized magnet M of the coin box at the calling station to collect the coin. This circuit is as follows: free pole of source C C, resistance lamp 5, conductor 178, lower armature and front contact of relay C, now locked to grounded sleeve wire 125, relay 190, conductor 179, left armature and front contact of relay B, upper armature and back contact of relay A, springs 167 and 166, tip conductor 164, polarized magnet M contact 13, to ground. Relay A released when ground was removed from the sleeve conductor 124 at the connector. The polarized magnet M operates to collect the coin as shown and described in said Forsberg patent. In operating, magnet M locks itself to ground by closing contact 11 and then releases the coin which opens contact 13. Due to the closure of contact 11, the magnet M remains operated as long as the coin current impulse lasts, as shown in said Forsberg patent. In case the first impulse from the interrupting machine fails to cause the collection of the coin, additional impulses are sent and the release of the primary line switch PLS is held up in the following manner:

When the relay B operated, in attracting its outer right armature it opened the locking circuit previously traced for slow relay H, but at the same time a substitute circuit is closed at the make-before-break contact of relay B, by way of conductor 4, to battery at the right break contact of relay T. The relay 190 operates in the coin current circuit in series with the polarized magnet

M, and closes a circuit to operate and lock relay T. With relay T operated and locked, the locking circuit for relay H is transferred to the armature and front contact of relay 190. Relay H as pointed out holds up relay H H which at its inner right armature is maintaining ground on the sleeve conductor 125 leading to the holding winding 100 of the primary line switch. Thus these two alternate circuits maintain relay H operated until the ground at the substation is removed. As long as relay Y remains operated, lamp 180 lights before an attendant.

Assuming, as in the normal case, that the coin is collected on the energization of magnet M by the first impulse the second time the relay B operates from the interrupter I no ground will be present at the substation and the relay 190 will fail to operate and the substitute circuit for relay H at the front contact of relay 190 will not be present. Relay H accordingly releases, releasing relay H H. Relay H H in retracting its inner right armature removes ground from the sleeve conductor 125 leading to the holding winding 100 of the line switch, resulting in the release of the same.

In case the called party did not respond, polarized relay P would not have shifted its armature and relay C would have remained inert. At its lower armature, this relay would have connected negative current from the 110 volt coin return source CR through resistance lamp 8 to the calling line to cause the polarized magnet M to refund the coin, lock up to ground at 12 and open contact 13. When the operating current is removed by the release of relay B, and magnet M releases opening contact 12, the primary line switch releases as described.

Certain lines called free lines are segregated upon connectors which do not reverse the current flow in the calling line when the called party responds. On such calls, battery is fed to the calling line over the impulse circuit previously traced, the relay R' being balanced by the retardation coil 188, the condensers 129, 130 separating the calling and called ends of the circuit.

The retardation coil 181 is provided in these calls to prevent short circuiting the voice currents.

Upon disconnection in this class of calls, inasmuch as relay C is not operated, the coin is refunded as in the case of unsuccessful calls.

Resistance 182 is connected to ground at one end and to the condensers 129 and 130 at the other end over normal contacts of relay D D. The other terminals of these condensers are connected over normal contacts of relay A to the armatures of relay B over which the relatively high potential coin current flows. This arrangement is for pre-

venting burning of the contacts of relay B when the high voltage coin current is cut off by the interrupter I releasing relay B.

The ground applied by the polarized magnet M is connected to the tip side 164 of the line and the ground through the relay 210 at the connector is also normally applied to the same side of the line. However, when the relay 211 is operated when the called party answers, battery is connected to the tip side of the line and to prevent this change from holding the switches set by holding relay 210 operated, relay J, which operates due to relay 211 operating, is provided to prevent the switches from remaining set after the parties replace their receivers.

More particularly, when the calling party restores his receiver, and the called party still has his off the hook, inasmuch as relay J is held up from ground on the sleeve wire 125, the circuit through the right winding of relay 210 and the coin ground is open at the switchhook of the calling line and thus the holding up of relay 210 to prevent the release of the switches, is avoided. Relay 210 therefore releases, opening the circuit of the usual slow relay 240. The release of the slow relay energizes the release magnet 241 which releases the connector and the release of the slow relay removes ground from the sleeve conductor 235, which releases the selectors. The selectors release before the coin collecting operations are completed and inasmuch as the ground on the release wire 125, to which relay J is locked, cannot be removed until these operations are completed the circuit referred to from the ground in the coin box to the right winding of relay 210 cannot be established.

When the called party restores first, relay 211 releases and reverses the current flow in the calling line. In this event relays J and K cooperate to prevent this condition from holding up the release of the switches. When the relay J operated upon the response of the called party, it reversed the current thus causing relay P to restore. It also closes at its armature 183 a circuit for relay K, this circuit including the conductors 151 and 157, and the grounded sleeve wire 125. Relay K is designed to be slow-to-pull-up, so that relay P will release before relay K operates to partly prepare a circuit to shunt relay J. When the called party replaces his receiver and reverses the current flow in the calling line, relay P operates and shunts out relay J over resistance 184, conductor 185, armature and front contact of relay K, contact of relay P, conductors 192 and 157, to grounded sleeve wire 125. Relay J restores the original connections to the tip and ring conductors so that the ground in the coin box is now connected to the tip side 164 of the line to which the

grounded side of relay 210 is connected. Thus, when the calling party subsequently restores his receiver, no circuit could be maintained closed from the coin ground to the winding of relay 210 to which the free pole of battery is connected. Thus release is not prevented. Relay P is located in the tip side of the line rather than the ring side so that if the called party hangs up immediately after the calling party and releases relay 211 thus reversing battery to the calling party before the slow relay in the connector has time to release and remove the ground from the sleeve wire which is holding up relay S', relay P will be operated when relay 211 releases over a circuit from the free pole of battery through right winding of relay 210 to the coin ground, thus short-circuiting relay J as described, which reconnects the coin ground to the left winding of relay 210 and reconnects the right winding of relay 210, which is connected to the free pole of battery, to the ring side of the line which is open at the calling line switchhook. Thus release is not interfered with.

Certain levels of the selector S or a preceding selector may contain trunks leading to operators' positions, such as information or toll operators. The induction coil 10 is provided to give such operators a tone to inform them of the character of the line. As shown in British Patent No. 15,133 of 1911, to Derriman, tone may be induced in the secondary winding 197 of the induction coil 10 from a class tone source CT which is transmitted by coil 186 to the sleeve wires 124, 235 and 237, and thence to the operator's head set, as shown and described in said patent.

If the calling party instead of dropping a coin, removes the receiver and fraudulently grounds the line in some manner, the impulse relay R' is placed under control of the dial as previously described. The calling party then sets the switches by means of the dial and establishes a connection with the called line. Before replacing his receiver, however, the calling party in order to prevent lighting lamp alarm 180 as described, removes said ground. The replacement of the receiver restores the calling line to its normal condition, and causes the coin collect circuit of Fig. 1 to function as described up to the point where relay B connects the collect source C C through relay 190 to the calling line. In the normal operation of the system relay 190 operates at this time and at its armature connects battery to relay T, which operates over an obvious circuit to ground at the sleeve wire 125. Relay T in attracting its right hand armature removes battery from conductor 4 and in attracting its left armature locks to grounded conductor 125. Since we have assumed the

70

75

80

85

90

100

105

110

115

120

125

130

ground to have been removed before the replacement of the receiver, relay 190 does not operate and lock up relay T as described so that when relay B is operated by the first impulse from interrupter I and attracts its outer right armature, the continuity contact controlled by said armature substitutes battery on conductor 4 from the normal right hand contact of relay T for the battery from the alternate contact of relay H to hold slow relay H operated to prevent the release of the primary line switch. The circuit for holding relay H operated is as follows: ground, relay H, conductor 174, continuity contact of relay B, conductor 4, to battery at the right hand normal contact of relay T, now inert due to relay 190 not having operated. When interrupter I again releases relay B, the outer right armature again applies battery to relay H before the battery connection described from the normal contact of relay T is opened by the opening of the continuity contact. It will be remembered that relay Y operated on the release of relay S' and the closure of the lower contact of interrupter I, and at its outer left armature locked itself to ground over the inner right armature of relay H and conductor 148. Relay Y at its right armature lights lamp 180. This lamp is located so as to be visible to an attendant who will know by its sustained illuminated condition that either the apparatus is not functioning properly due to trouble or that someone is trying to "beat" the coin box. Since the calling line is under these conditions held extended to the primary line switch, its number may be readily determined, and the matter investigated.

40 What is claimed is:

1. In a telephone system, a calling line having a sender and a coin controlled mechanism, an automatic numerical switch, an impulse circuit for setting said switch, means for automatically extending the calling line to said switch, means operated by the deposit of a coin for altering the calling line circuit, a test relay responsive to said alteration for placing said impulse circuit under control of said sender, means for applying current to said line to actuate said mechanism to dispose of the coin, an alarm signal, and means responsive to the normal condition of the calling line circuit to actuate said signal.
2. In a telephone system, a calling line having a sender and a coin controlled mechanism, an automatic numerical switch, an impulse circuit for setting said switch, means for automatically extending the calling line to said switch, means operated by the deposit of a coin for altering the calling line circuit, a test relay responsive to said alteration for placing said impulse circuit under control of said sender, means for

applying current to said line to actuate said mechanism to dispose of the coin, a lamp, and means thereafter responsive to the normal condition of the calling line circuit for continuously lighting said lamp.

3. In a telephone system, a calling line having a sender and a coin controlled mechanism, an automatic numerical switch, an impulse circuit for setting said switch, a non-numerical switch for extending the calling line to said numerical switch, means operated by the deposit of a coin for altering the calling line circuit, a test relay responsive to said alteration for placing said impulse circuit under control of said sender, means for applying current to said line to actuate said mechanism to dispose of the coin, an alarm signal, and means responsive to the normal condition of the calling line circuit to actuate said signal and hold said non-numerical switch in its operated position when said current is applied to the calling line.

4. In a telephone system, a calling line having a sender and coin collect mechanism, an automatic numerical switch, an impulse circuit for setting said switch, means for automatically extending the calling line to said switch, means operated by the deposit of a coin for grounding the calling line, a test relay responsive to said ground for placing said impulse circuit under control of said sender, means for applying current to said line to actuate said mechanism to dispose of the coin, an alarm signal, and means responsive to the normal condition of the calling line circuit to actuate said signal when said current is applied to the calling line.

5. In a telephone system, a calling line having a sender and a coin controlled mechanism, an automatic numerical switch, an impulse circuit for setting said switch, means for automatically extending the calling line to said switch, means operated by the deposit of a coin in said mechanism for grounding the calling line, a test relay responsive to said ground for placing said impulse circuit under control of said sender, means for actuating said mechanism to dispose of the coin, means in said coin controlled mechanism for thereafter removing said ground from the line, an alarm signal, means to actuate said signal, and means responsive to the coin controlled ground and the removal thereof for restoring said signal.

6. In a telephone system, a calling line comprising a sender and a coin controlled mechanism; an automatic numerical switch; an impulse circuit for setting said switch; means for automatically extending the calling line to said switch; means actuated by the deposit of a coin for grounding one side of the line via the coin mechanism; a test relay responsive thereto for placing

said impulse circuit under control of said sender; a grounded source of current; means for connecting said source to the line to actuate said mechanism to dispose of the coin; an alarm signal; and means, responsive when said source of current is connected to the calling line in the absence of a coin, for actuating said alarm signal.

7. In a telephone system; a calling line; 10 a sender and a coin controlled magnet; an automatic numerical switch; an impulse circuit for setting said switch; means for automatically extending a calling line to said switch; means, actuated by the deposit of 15 a coin, for connecting the coin magnet from one side of the line to ground; a test relay responsive thereto for placing said impulse circuit under control of said sender; a grounded source of current at the central 20 office; means for connecting said source to said line to actuate said magnet to dispose of the coin; means for disconnecting said source from said line to remove the ground therefrom by restoring said magnet; an 25 alarm signal; and means, responsive to the improper application to, or removal of ground from, said line, to actuate said signal.

8. In a telephone system, a calling line, 30 a sender and a coin controlled magnet, an automatic numerical switch, an impulse circuit for setting said switch, means for automatically extending a calling line to said switch, means actuated by the deposit of a 35 coin for connecting the coin magnet from one side of the line to ground, a test relay responsive to the grounding of the line for placing said impulse circuit under control of said sender, a grounded source of current 40 at the central office, means responsive to the replacing of the receiver of the calling line for connecting said source to the line whereby said magnet is operated to dispose of the coin, an alarm signal, and means responsive 45 to the improper removal of ground from said line to actuate said signal when said current source is connected to the calling line.

9. In a telephone system; a calling line; a 50 sender and a coin controlled magnet; an automatic numerical switch; an impulse circuit for setting said switch; means for automatically extending a calling line to said switch; means actuated by the deposit of a 55 coin for connecting the coin magnet from one side of the line to ground; a test relay responsive to the grounding of the line for placing said impulse circuit under control of said sender; a grounded source of current 60 at the central office; means responsive to the replacing of the receiver of the calling line for alternately connecting said source to, and disconnecting said source from, the calling line; an alarm signal; means for actuating 65 said signal until the current source is

no longer connected to the calling line; a circuit including said current source and magnet for operating the magnet to dispose of the coin; and means effective after the coin has been disposed of, for completely disassociating the source of current from the calling line. 70

10. In a telephone system, a calling line, a sender and a coin controlled magnet associated therewith, an automatic numerical 75 switch, an impulse circuit for setting said switch, means for automatically extending the calling line to said switch, means actuated by the deposit of a coin for altering the calling line circuit, a test relay at the central office responsive to the circuit alteration for placing said impulse circuit under control of said sender, a source of current for operating said coin controlled magnet, means responsive to the opening of the calling line circuit for connecting said source of current to the calling line, an alarm signal at the central office, and means responsive to the normal condition of the calling line for actuating said signal when said current source is applied thereto. 80

11. In a telephone system, a calling line including a sender and a coin operated mechanism, means in said mechanism responsive to the deposit of a coin for grounding the calling line, an automatic switch, a circuit controlled by said sender for setting said switch, means responsive to the grounding of the calling line for completing said switch setting circuit, a source of current supply, means for connecting said current source to the calling line to operate said mechanism to dispose of a coin, an alarm signal, and means responsive whenever a coin is not disposed of for actuating said signal. 105

12. In a telephone system, a calling line including a sender and a coin operated mechanism, means in said mechanism responsive to the deposit of a coin for grounding the calling line, an automatic switch, a called line, a circuit controlled by said sender for setting said switch to build up a connection to the called line, means responsive to the grounding of the calling line for completing said switch setting circuit, means responsive to the partial breaking down of the connection to operate said mechanism to dispose of the coin, an alarm signal, means for preventing the complete breaking down of the connection unless a coin is disposed of, and means responsive during the breaking down of the connection to actuate said signal. 110

13. In a telephone system, a calling line including a sender and a coin operated mechanism, means in said mechanism responsive to the deposit of a coin for grounding the calling line, an automatic switch, a called line, a circuit controlled by said 125

- sender for setting said switch to build up a connection to the called line, means responsive to the grounding of the calling line for completing said switch setting circuit, means 5 responsive to the partial breaking down of the connection to operate said mechanism to dispose of the coin and to restore said mechanism to normal, an alarm signal, means responsive to the breaking down of 10 the connection for actuating said signal, and means for preventing the total breaking down of the connection unless the coin mechanism first operates to dispose of the coin.
- 15 14. In a telephone system; a calling line including a sender and a coin operated mechanism; means in said mechanism responsive to the deposit of a coin for grounding the calling line; an automatic switch; a 20 called line; a circuit controlled by said sender for setting said switch to build up a connection to the called line; means responsive to the grounding of the calling line for completing said switch setting circuit;
- 25 means responsive to the replacing of the receiver at the calling station for initiating the breaking down of the connection; a source of current supply; a circuit including the calling line, the coin operated mechanism and the current source; a device 30 operable to close the circuit aforesaid by connecting the current source to the calling line; an alarm signal; means, operated while the breaking down of the connection is in progress, for actuating said signal, and for 35 intermittently operating said circuit closing device; means in said coin operated mechanism for disposing of the coin the first time said circuit is closed; means in said coin operated mechanism for removing the ground 40 from the calling line the first time said circuit is opened providing the coin has been disposed of; and means for retaining the connection with the calling line and for continuing to actuate said signal providing a 45 coin has not been disposed of by said coin controlled mechanism.

In witness whereof, I hereunto subscribe my name this 28th day of December A. D., 1922.

ROY D. CONWAY.
